UNITED STATES PATENT OFFICE.

MILTON L. DODGE, OF NEWBURYPORT, MASSACHUSETTS.

SHOE HAVING A MOLDED COUNTERSTIFFENER THEREIN AND METHOD OF MAKING THE SAME.

Application filed June 16, 1923. Serial No. 645,859.

This invention relates to shoes having molded counter stiffeners therein and improvements in their method of manufacture.

As heretofore constructed such counter stiffeners have been provided with inturned marginal flanges at their lower edges by which they may be fastened to the shoes. This attaching flange has been formed by passing a wiper laterally over one face of a die from which the edge portion of a stiffener protrudes. The molding and flange-forming operations are done while the stiffener is in temper and in the subsequent drying operation the flange bends back somewhat so that its outer face is not in a plane but is somewhat convex downwardly. This action takes place both longitudinally and laterally of the stiffener and prevents the counter stiffener at the outer edge of the flange from making close contact with the shoe sole. This defect detracts from the appearance of the finished shoe since the upper is spaced from the counter adjacent the sole and is permitted to draw up sharply from the edge of the sole at the sides and rear of the shoe. This also has the effect of rendering the heel seat of the shoe, particularly when cut to receive a wood heel, so sharply convex as to cause considerable difficulty in effecting a close joint between the upper margin of the heel and the upper since the permissible depth of the cavity in the upper face of the heel is limited by the necessary thickness of its margin for the proper strength. At its forward edge the counter is often raised from the sole forming a considerable space between the shank piece and the upper face of the shoe. This lowers the apparent height of the arch since it is higher within the shoe than on the outside.

According to the present invention after the counter stiffener flange is formed, and preferably while the counter is still in temper, it is placed in a press and the flange pressed inwardly beyond the plane of its outer edge, and at least as far back from its forward end as the stitch line between the sole and the upper of the completed shoe. This flange is formed with an outwardly projecting bead back from the inner edge,

which when the counter is in position, contacts with the sole outwardly of the seam between it and the upper, this seam underlying the inner edge of the flange. It is within the scope of this invention, however, to form this bead when the flange is formed instead of in a subsequent operation. When the counter is assembled in the shoe, fastenings such as stitches or staples are then passed through the bead outwardly of the stitch line between the upper, through the between substance and inner portion of these fastenings being seated within the channel of the sole, or if desired, a filling or shank piece made fast to the stiffener flanges and to the sole may be relied on to hold the bead tight against the shoe upper outwardly of the stitch line, or both shank piece and fasteners may be employed. The upper having been turned this rib retains the upper close against the upper face of the sole and holds it to a nicely rounded form, thus effecting a very material improvement in the appearance of the shoe as well as uniting the various parts in a more secure manner.

For a more complete understanding of this invention reference may be had to the accompanying drawings in which—

Figure 1 is a perspective of a counter stiffener constructed according to this invention.

Figure 2 is a fragmentary longitudinal section through the heel portion of a shoe showing the stiffener in position.

Figures 3 and 4 are fragmentary sections on the plane of line *a*—*a* of Figure 2 showing the shoe before and after the heel end has been turned.

Figure 5 is a fragmentary side elevation, parts being broken away of a shoe illustrating defects which the construction of this invention is designed to avoid.

Figure 6 is a section on line 6—6 of Figure 5.

Referring first to Figures 5 and 6, the counter is indicated at 1 having an inturned marginal flange 2 by which it may be attached to the upper face of the shoe sole and which in turn has superposed thereon the usual shank piece 3. Where the flange 2 of

the counter is downwardly convexed it does not lie closely against the shoe sole so that the marginal portion of the counter stiffener adjacent this flange is positioned above the sole. This leaves a space which is bridged by the upper 4 which is unsupported between the stitch line 5 with the sole and a portion of the stiffener 6 somewhat above the sole. This causes the shoe to present a flat appearance adjacent the sole which in use soon shows wrinkles and detracts from the appearance of the shoe. Likewise the forward end of the counter stiffener may be raised up from the sole as shown at 7 in Figure 5 forming a space between the shank piece 8 and the upper face of the sole so that the shoe actually has a higher arch than appears from the contour of the lower face of the sole. This also detracts from the appearance of the shoe besides being a source of weakness since the parts are not strongly united. The heel seat portion of the shoe may also be so sharply convex as to prevent the upper margins of a wood heel from closely engaging the upper as is shown in Figure 6 at 9.

To obviate these objections according to this invention, after the stiffener has been molded and the edge flange formed about its lower margin in the usual manner, it is placed in a press and the inner margin of the flange bent upwardly sufficiently so that when the counter is dry it may not spring outwardly beyond the plane of its outer margin. At the same time a bead, indicated at 10 in Figure 1, is pressed downwardly at the junction between the side of the stiffener and the flange, this bead extending rearwardly at least as far as the stitch line between the sole and upper in the finished shoe and it may, if desired be extended completely around the stiffener. The lower face of the stiffener then lies substantially in a single plane, and if desired may be slightly bowed upwardly longitudinally or bent down at its forward end to closely fit the rear portion of the shank over which it may extend.

After the upper has been made fast to the sole of the shoe, as shown in Figure 3, the counter is placed in position on the sole before the heel portion of the shoe has been turned, the bead 10 resting on the upper 11 outwardly of the stitch line 12 which unites the upper and sole. As shown this stitch line extends through the between substance of the sole, the stitches being seated within the usual channel 13. Fastenings such as staples or stitches, shown at 14, are then passed through the base of the bead 10, the upper 11 and the between substance of the sole and are seated within the channel 13 beneath and outwardly of the stitches 12. This causes the flange at the forward portion of the counter stiffener to lie tightly

against the upper so that when the shoe is turned as in Figure 4 the upper embraces the outer face of the stiffener from the stitch line 12 upwardly so that there is no opportunity for the space therebetween and the flat portion of the upper as shown in Figure 6. Likewise the forward edge of the counter is pulled tightly against the sole forwardly of the heel whereby it is not possible to nail the flange to the sole, so that the shank piece shown at 8 rests closely against the upper face thereof. When a shank piece 8 is employed it is made fast to the counter flange and if a long shank piece is employed its forward end is made fast to the sole and so thus acts to hold the forward end of the stiffener down and bring the bead against the upper outside of the stitch line, and if it extends that far, forwardly of the heel seat where it is not possible to nail the stiffener to the sole. If the shank piece extends only to the forward edge of the stiffener or thereabout, and it is not attached to the sole at its forward end, its stiffness acts to hold the bead in position. This shank piece may extend forwardly of the counter stiffener as shown in Figure 2 or it may terminate substantially in line with its forward edge as may be desired. By this means the appearance of the arch is materially improved as well as the contour of the upper extending from the sole immediately forward of the heel. This construction also materially flattens the heel seat portion of the shoe so that a wood heel having its upper face formed concave may closely engage the upper about the margin of the heel seat without requiring an excessive depth of cavity in the upper face of the heel.

While this invention has been shown as applied to turn shoes it may also be applied to shoes of other types such as welts and McKays.

Having thus described an embodiment of this invention, it should be evident that various changes and modifications may be made therein without departing from its spirit or scope as defined by the appended claims.

I claim:

1. A shoe comprising a sole, a counter stiffener having a sole attaching flange, an upper enclosing said stiffener and made fast to said sole, and means for fastening the flange of said counter stiffener to said sole outwardly of the attaching line between said upper and sole.

2. A shoe comprising a sole, a counter stiffener having a sole attaching flange, an upper enclosing said stiffener and made fast to said sole, and means for holding the flange of said counter stiffener to said sole outwardly of the attaching line between said upper and sole and forwardly of the heel seat.

3. A shoe comprising a sole, a counter stiffener having a sole attaching flange, an upper enclosing said stiffener and made fast to said sole, and means for fastening the flange of said counter stiffener at its forward ends to said sole outwardly of the attaching line between said upper and sole.
4. A shoe comprising a sole, a counter stiffener having a sole attaching flange, an upper enclosing said stiffener, means for fastening said upper to said sole through the between substance thereof, and means for attaching said flange to the sole through the between substance.
5. A shoe comprising a sole, a counter stiffener having a sole attaching flange, an upper enclosing said stiffener, means for fastening said upper to said sole through the between substance thereof, and means for attaching said flange at its forward ends to the sole through the between substance.
6. A shoe having a counter stiffener provided with a marginal flange, a sole, an upper attached to said sole and overlaid by said flange, said flange having a downwardly extended bead resting on the upper outside the line of its attachment to the sole, and means for fixing said bead to said sole forwardly of the shoe heel seat.
7. A shoe having a counter stiffener provided with a marginal sole attaching flange, said flange being formed with a downwardly extending bead back from its free edge, a sole, and means passing through said bead for attaching said stiffener to the sole.
8. A shoe having a counter stiffener provided with a marginal sole attaching flange, said flange being formed with a downwardly extending bead back from its free edge, a sole, and means passing through said bead for holding said stiffener to the sole forwardly of the heel seat.
9. A shoe having a counter stiffener provided with a marginal sole attaching flange, said flange being formed with a downwardly extending bead back from its free edge, a sole, and means for attaching said stiffener to the sole passing through said bead and the between substance of the sole.
10. A shoe having a counter stiffener provided with a marginal flange, a sole and an upper attached to the margin of said sole, said flange having a downwardly extending bead back from its edge resting on the upper outside the line of its attachment to the sole, and a fastener passed through said bead, the upper, and between substance of the sole.
11. A shoe having a counter stiffener provided with a marginal flange, a sole and an upper attached to the margin of said sole, said flange having a downwardly extending bead back from its edge resting on the upper outside the line of its attachment to the sole, and a fastener passed through said bead, upper, and sole.
12. The method which comprises forming a downwardly extending bead back from the edge of the sole attaching flange of a molded counter stiffener at its forward ends, assembling said counter stiffener in a shoe with said bead bearing on the shoe upper outwardly of the stitch line between the upper and the sole, and inserting fasteners through said bead, upper and sole.
13. The method which comprises forming a downwardly extending bead back from the edge of the sole attaching flange of a molded counter stiffener at its forward ends, assembling said counter stiffener in a shoe with said bead bearing on the shoe upper outwardly of the stitch line between the upper and the sole, and attaching the stiffener in position forwardly of the heel seat.
14. The method which comprises forming a downwardly extending bead back from the edge of the sole attaching flange of a molded counter stiffener at its forward ends, assembling said counter stiffener in a shoe with said bead bearing on the shoe upper, and attaching the stiffener in position through said bead.
15. The method which comprises forming a downwardly extending bead back from the edge of the sole attaching flange of a molded counter stiffener at its forward ends, assembling said counter stiffener in a shoe with said bead bearing on the shoe upper outwardly of the stitch line between the upper and the sole, and inserting fasteners through said bead, upper, and sole outwardly of said stitch line.
16. The method which comprises forming a downwardly extending bead back from the edge of the sole attaching flange of a molded counter stiffener at its forward ends, assembling said counter stiffener in a shoe with said bead overlying and bearing on the shoe upper outwardly of the stitch line between the upper and the sole, and holding said bead against the sole forwardly of the heel seat.
17. The method which comprises forming a downwardly extending bead back from the edge of the sole attaching flange of a molded counter stiffener at its forward ends, assembling said counter stiffener in a shoe, and passing fastening means through said bead and the shoe upper and sole.
18. The method which comprises forming a downwardly extending bead back from the edge of the sole attaching flange of a molded counter stiffener at its forward ends, assembling said counter stiffener in a shoe with said bead bearing on the shoe upper outwardly of the stitch line between the upper and the sole, and inserting fasteners through said bead, upper and sole outwardly of said stitch line and passing through the between substance of the sole.
19. The method which comprises forming

a downwardly extending bead back from the edge of a sole attaching flange of a molded counter stiffener at its forward ends, assembling said counter stiffener and a shank piece in a shoe with said bead bearing on the shoe upper outwardly of the stitch line between the upper and sole, and attaching

the forward portion of the shank piece to the sole whereby to hold said bead against the upper forwardly of the heel seat of the ¹⁰ sole.

In testimony whereof I have affixed my signature.

MILTON L. DODGE.
